UNITED STATES PATENT OFFICE.

WILLIAM B. COGGER, OF SPRINGFIELD, ILLINOIS.

ADJUSTABLE FURNITURE.

SPECIFICATION forming part of Letters Patent No. 687,675, dated November 26, 1901.

Application filed January 2, 1901. Serial No. 41,924. (No model.)

To all whom it may concern:

Be it known that I, WILLIAM B. COGGER, a citizen of the United States, residing at Springfield, in the county of Sangamon and State of Illinois, have invented a new and useful Improvement in Adjustable Furniture, of which the following is a specification, reference being had to the accompanying drawings, in which—

10 Figure 1 is a horizontal sectional view showing the clamping and adjusting mechanism. Fig. 2 is a sectional view on line A A, Fig. 1. Figs. 3, 4, and 5 are details hereinafter referred to.

15 My invention relates to improvements in adjustable furniture; and the object of my invention is to provide a readily-accessible means of adjusting articles of furniture.

One feature of my invention is the means 20 adopted for securing the pinion to the shaft. The hollow shaft upon which is mounted the pinion is formed with a keyway, and the pinion is formed with keys or lugs which engage in these keyways.

25 Another feature of my invention lies in the means adopted to turn the shaft upon which the pinion is mounted. The washer which lies between the clamping-nut and the standard is polygonal in outline and is secured to 30 the adjusting-shaft by means of keys formed on the inside of the washer engaging in keyways formed on the shaft. The washer being on the outside of the standard is readily accessible to be engaged by a wrench, and 35 when the washer is turned the shaft turns with it to operate the adjusting mechanism.

In the drawings illustrating the principle of my invention and the best mode now known to me of applying that principle, *a* represents the

40 supporting-standards, which are secured to the floor, and *b* the bracket members, secured to the article of furniture. (Not shown.) Journaled in the standards *a* is a hollow shaft *c*, formed with keyways *d*, in which engage the 45 lugs *e*, which are formed on the inside of the pinions *f*. (See Fig. 5.) The pinions *f* engage toothed racks *g*, (see Fig. 2,) formed on the brackets *b*, so that by the rotation of the shaft *c* the brackets *b* are raised or lowered.

50 To rotate the shaft *c*, I provide the washers *h* with lugs *i*, which engage the keyways *d* on the shaft *c*, and make the washers polygo-

nal in outline, so that they may be readily engaged by a wrench. (See Figs. 3 and 4.) Extending through the shaft *c* is a bolt *j*, 55 screwed on the ends of which are the nuts *k*. When the nuts *k* are screwed up tight, the stress tending to force the standards together is taken up by the shaft *c*, which acts as an abutment between the standards *a*. Again, 60 when the nuts *k* are screwed up any wear between the rubbing surfaces is taken up.

What I claim is—

1. In adjustable furniture, the combination of an adjusting-shaft with means for the rotation of said shaft; said means comprising a washer having its surface constructed to engage a wrench and secured to said shaft by a key on the one engaging a keyway in the other. 65

2. In adjustable furniture, the combination of an adjusting-shaft with means for the rotation of said shaft; said means comprising a washer polygonal in outline and secured to said shaft by a key on the one engaging a keyway in the other. 70

3. In adjustable furniture, the combination of an adjusting-shaft; a pinion secured to said shaft by a key on the one engaging a keyway in the other; and means to rotate said shaft; said means comprising a washer secured to 80 said shaft by a key on the one engaging a keyway in the other, and having its surface constructed to engage a wrench.

4. In adjustable furniture, the combination of supporting-standards; a shaft journaled in 85 said standards; clamping means; and washers interposed between said clamping means and said standards; said washers being secured to said shaft by a spline-and-groove connection and thereby adapted to rotate said 90 shaft.

5. In adjustable furniture, the combination of supporting-standards; a hollow shaft journaled in said standards; a bolt extending through said shaft; nuts on the ends of said 95 bolt; and washers interposed between said nuts and said standards; said washers being secured to said shaft by a spline-and-groove connection and thereby adapted to rotate said shaft. 100

6. In adjustable furniture, the combination of supporting-standards; a shaft journaled in said standards; pinions secured on said shaft by a spline-and-groove connection; the spline

on the pinion abutting against the inner wall of the groove in the shaft; brackets formed with racks adapted to engage said pinions; clamping means; and washers interposed between said clamping means and said standards.

7. In adjustable furniture, the combination of supporting-standards; a shaft journaled in said standards; pinions secured on said shaft by a spline-and-groove connection; brackets formed with racks adapted to engage said pin-

ions; clamping means; and washers interposed between said clamping means and said standards, said washers being secured on said shaft by a spline-and-groove connection.

Dated at Bloomsburg this 19th day of December, A. D. 1900. 15

WILLIAM B. COGGER.
